NONLOCKOUT COMBINATION TIME DELAY LOCK

Charles M. Hirn, Cincinnati, Ohio, assignor to
The Mosler Lock Company, Covington, Ky., a
corporation of Ohio

Application April 27, 1939, Serial No. 270,406

7 Claims. (Cl. 70—274)

The present invention relates to time delay combination locks and has for an object the provision of a highly efficient device embodying a relatively inexpensive time movement and providing relatively simple means to avoid a lock-out in the event the time mechanism breaks down or stops for any reason during the period in which the successful opening of the lock depends upon the complete running down of the time mechanism.

A further object of the invention is to provide an inexpensive time delay combination lock wherein the tumbler mechanism and the time movement are disposed in side by side relation in a relatively flat case and are adapted, by simple and novel means, to selective interengagement enabling the lock to be used as an ordinary combination lock or, if desired, as a time delay combination lock under a variety of circumstances.

These and other objects are attained by the means herein described and shown in the accompanying drawings, in which:

Fig. 1 is a top plan view of a lock of the invention operatively mounted upon a door and having the top wall of the lock casing cut away.

Fig. 2 is a view taken on line 2—2 of Fig. 1.

Fig. 3 is a view of the interior of the lock casing with the cover and its attached combination lock and time movement removed but showing the position of parts when the time mechanism is fully wound and at rest and the bolt is locked, parts being broken away.

Fig. 4 is a view similar to Fig. 3 but showing the position of parts wherein the time movement is fully unwound and the bolt is unlocked and latched in unlocked position.

Fig. 5 is a view similar to Fig. 4 but showing the relation of parts when the time movement is fully wound and the bolt is locked and the driver of the combination lock is ready to start the time movement.

Fig. 6 is a view similar to Fig. 4 but showing the relation of parts when the time movement is partly unwound.

Fig. 7 is a view similar to Fig. 6 showing the relation of parts wherein the partly unwound time movement has been disabled and the means to preclude a lockout is in position to be operated.

In my United States Letters Patent No. 2,152,258, issued March 28, 1939, there is shown a time delay combination lock which is useful as an ordinary combination lock or as a delayed opening combination lock by the mere selection of the initial direction of movement of the tum-

bler operating knob. The said lock also affords means to prevent the throwing of the bolt after the lock has been operated as a time delay lock, without first conditioning the time movement to fully wound condition.

The device of the present invention embodies these same functions and in addition thereto provides simple means permitting a flatter and more compact arrangement of the parts and furthermore provides a foolproof arrangement to avoid lockouts due to failure of the time movement.

Referring to the drawings, the device of the present invention is arranged to be mounted upon any suitable door 10 and consists of the usual ring 11, combination number dial 12 and operating knob 13. An arbor 14 is fixed to the knob and dial and extends through the door into the flat shallow lock casing 15. The bottom wall 16 of the casing abuts the door 10 and is secured in place by one or more screws such as 17. Surrounding the arbor 14 interiorly of the casing is an annular boss 18, the exterior circumference of which serves to position and limit the movement of an odd-shaped floating lever 19 which slides upon the inner face of base 16 and is normally influenced to the position shown in Fig. 2 by a spring 20 which is anchored to one of the posts 21 that receive the fastening screws 22 for the casing cover 23. Fixed in the base 16 are short pins 24 and 25 between which a finger 26 of floating lever 19 extends. Pivoted at 27 is a lever 28 which extends alongside floating lever 19 and is adapted under extraordinary conditions and in the fashion hereinafter detailed to shift lever 19 against the influence of its spring 20 and other forces from a position wherein the finger 26 is shifted from a position against pin 25 to a normal position abutting pin 24. A bell crank lever 29 is pivotally mounted on base 16 and has at its one end a hook 30 and at its opposite end a finger 31. Spring 32, seated in a slot in lever 29 and abutting a stud 33 serves to urge the hook end of the lever toward the projecting finger 26 on floating lever 19.

The members 19 and 29 play important parts in the normal operation of the device when used as an ordinary combination lock or as a time delay combination lock. The secret lever member 28 is utilized only in the event of a lock-out due to the failure of the time movement after partial operation and serves specifically as a means, actuatable through the agency of a secret combination of the lock tumblers operated by the knob and dial, to move the floating lever 19 from the position shown in Fig. 6 to the position

shown in Fig. 7. It will be noted that a shouldered notch 34 in the forward end of floating lever 19 is positioned so as to baffle or hold the gate 35 out of contact with the tumblers against the yielding resistance of spring 350, wherefore in that position the lock cannot be operated even though the tumbler notches are aligned with the gate. Floating lever or gate baffling means 19 is arcuately cut away as at 36, immediately adjacent to a jacent shouldered notch 34 so as to permit gate 35 to contact the tumblers and to enter the notches thereof when the notches are aligned by a properly set up combination. The bolt comprises a relatively heavy member 37 adapted to reciprocate through a correspondingly shaped aperture in the end wall of the lock casing to and from a suitable keeper, (not shown). A plate-like portion 38 integral with the locking bolt 37 has an oblique slot 39 therein through which a depending pin or projection 40 extends to cooperate with the shouldered notch 34 on floating lever 19. The size and shape of slot 39 is such as to effect manipulation of bolt 38 by the coaction of the slot 41 in driver 42 with the lower portion of gate 35. Bolt 38 has an elongated central guide slot 43 therethrough which receives the short upstanding cylindrical flange 44 on boss 18. A pair of screws 45 have the heads thereof overhanging a reduced edge thickness portion 450 and the bolt is thus guided for longitudinal reciprocation. At the rear of the bolt is a shoulder 46 and at one side thereof a pin 47 projects downwardly below the bottom of the plate and is adapted under certain circumstances to be engaged by the hook 30 on bell crank lever 29 to latch the bolt 38 in open position (see Fig. 4).

Pivoted between the base 16 and cover 23 is a time setting post 48 which is spring urged in either direction by a spring 49 to assure entry of an integral lever 50 thereon into the notch 41 in driver wheel 42 (see Fig. 5). Below lever 50 and fixed to the time setting post 48 is a time setting finger 51 which cooperates with finger 31 when the lock is conditioned to release the time movement. The top of post 48 is cut away to form a cam or cam nose 52 which is adapted to be engaged by an extrusion 53 on the first or number one tumbler indicated at 54 (see Fig. 1). From the foregoing it will appear that when the extrusion 53 engages cam 52 by the proper setting of number one tumbler the time setting post may be turned upon its axis and held in the position shown in Fig. 3, wherein finger 51 is held substantially against the side of the casing wall and lever 50 is restrained against possible entry into the notch 41 of the driver. The parts hold this position when the combination lock is used without the cooperation of the time delay movement, viz., when the lock is used as an ordinary combination lock only. If the tumblers are initially turned so that number one tumbler has the extrusion 53 thereof moved past cam 52 so that lever 50 may enter notch 41 of the driver and turn the time setting post on its axis, then finger 51 will pass by the yieldably positioned finger 31 on bell crank lever 29. If the finger 51 is now forcibly returned, it will again engage finger 31 and rock the bell crank lever on its axis to start the operation of the time movement by the means and in the manner which will now be described.

Secured to the cover 23 in any suitable fashion is a time movement 55 which has a squared driving shaft 550 adapted to enter a corresponding

aperture 56 in time wheel 57. The time wheel has a frictionally retained finger 58 thereon. A conventional tension washer and locking ring assembly 570 serves this purpose. The time wheel also has a peripheral notch 59 into which an abutment such as upstanding pin 60 on the finger portion 26 of floating lever 19 may seat. The abutment 60 is resiliently retained against time wheel 57 at all times by reason of the pressure exerted on the floating lever by the spring 20. Projecting through and depending from the lower face of time wheel 57 is a pin 61 which may pass through a groove 62 in the hooked portion of bell crank lever 29 but cannot pass the finger 31 thereof. An external winding stem 63 has a key receiving socket 64 whereby, upon the reception of a square ended winding key, the time movement is wound and the time wheel is manually turned permitting the pin 61 to pass through the major portion of a circumference, during winding movement in the direction of the dotted arrow in Fig. 4. The pin passes through the groove 62 and continues until said pin 61 engages finger 31 and thereafter turns the bell crank lever to the position shown in Fig. 3. At this time notch 59 receives abutment 60 which is at all times yieldably urged toward the time wheel. Upon the completion of one revolution of the winding stem and the time wheel by manual operation, the time mechanism is held at rest in fully wound condition by suitable means commonly provided upon commercially available time movements. One example of this holding mechanism is illustrated and described in my hereinbefore mentioned United States Letters Patent No. 2,152,258. In order to start this time movement after being fully wound and arrested as aforesaid, it is necessary to manually turn the time wheel for a short distance in order to unseat the holding means. This movement is effected by first setting the finger 51 of the time setting post 48 in the position shown in Fig. 5 and then turning the driver 42 so that lever 50 will be engaged thereby to rock the time post and move finger 51 which in turn imparts a limited movement to finger 31 of the bell crank lever 29. This limited movement is transmitted to the time wheel 57 by reason of the engagement of finger 31 upon pin 61. This limited movement furthermore cams the abutment 60 out of the notch 59 in the time wheel 50 against the resistance of spring 20 whereupon the gate baffle or floating lever 19 assumes and retains the position which is best shown in Fig. 6 wherein the shoulder 34 holds gate 35 out of contact with the driver and the combination lock tumblers. When the notch 59 is brought into registry with the abutment pin 60 at the end of one revolution of the time wheel, the pin 60 drops into notch 59 and thus allows floating lever or gate baffle 19 to shift, under the influence of spring 20 to the inoperative position shown in Fig. 3, whereupon the gate 35 contacts the periphery of the tumblers. When the tumbler notches and driver notches are aligned by setting up the lock combination in known fashion, the gate 35 may enter said aligned notches and the pin 40 on the bottom of the gate is free to move through the slot 39 in the bolt. Upon further operation of the dial knob, in known fashion, the gate retracts the bolt and the pin 47 at the rear end of the bolt is engaged by the hook 30 on the bell crank lever thus latching the bolt in unlocked condition, making it impossible to again shoot the bolt without first manually winding the time movement at the winding arbor 63. The time

movement is ordinarily constructed to run for an interval sufficient to baffle daylight holdups, viz., from fifteen to thirty minutes.

- The foregoing explanation detailed the operation of the mechanism as a time delay combination lock. The external operation of the dial knob 13, in order to bring the time movement into operation is as follows: Having wound the time movement fully (while the door is open) 5 the door is closed and the bolt shot in the ordinary known manner. The dial may be turned at least four times to the right and allowed to stop on any number except within five marks of the first number. At this time the operator may 10 elect to operate the device either as an ordinary combination lock or as a time delay combination lock. To prepare the lock so that it may be opened only as a time delay combination lock, the dial is turned one or more complete revolutions to the left and allowed to stand on any 15 number upon which the mechanism is positioned as shown in Fig. 5. If now the dial is turned to the right, finger 51 is caused to rock toward the adjacent side of the casing and move finger 31 and pin 61, thus starting the time movement. Floating lever or gate baffle 19 is projected to the operative position shown in Fig. 6 wherein the gate 35 is held free of the tumblers and driver so that it is impossible to open the lock regardless of whether or not the correct combination is set up. When the time wheel completes its 20 revolution, the pin abutment 60 again enters notch 59 of the time wheel, thus allowing floating lever 19 to release the gate. 25
- It will be apparent that should the time mechanism fail before completing its revolution after once having been started, it would be quite impossible to remove the floating lever 19 from the position shown in Fig. 6 so that a lock-out would 30 result. In order to prevent a lock-out under such circumstances, an auxiliary gate 65 is provided and it has a bottom portion projecting into an aperture 66 in the lever 28 at the side of floating lever 19. Auxiliary gate 65 may have 35 the tumbler slots and driver slots aligned opposite its edge by the operation of a secret combination which, in the present instance, will be that of the ordinary combination plus a predetermined additional number of marks representing the circumferential distance between the 40 position of gate 35 and the position of auxiliary gate 65. Having set up the secret combination the auxiliary gate may enter the tumbler slots whereupon a pressure imposed on the tumblers 45 by forcibly turning the dial knob toward the left will cause the depending portion of gate 65 to rock lever 28 toward the left sufficiently to rock floating lever or gate baffle 19 likewise to the left and thus unseat the notch 34 from gate 35. 50
- During this movement the finger 26 of the floating lever moves to the right and abuts pin 25. Since gate 35 has now been released, the normal 55 combination may be set up and the lock opened.

In order to prevent the successful use of the 60 secret combination at any time save when the time mechanism is actually disabled, the frictionally retained finger 58 is constantly urging pin 60 on finger 26 toward stop pin 24 while the time wheel is in motion, therefore if the secret 65 combination is set up while the time wheel 57 is slowly moving under the influence of the time movement and in the direction of the solid line arrow in Fig. 6, it will be apparent that even though the secret combination is employed to 70 effect the movement of lever 28 and floating lever 75

19, the frictionally driven finger 58 on the time wheel pressing on pin 60 will carry the floating lever back to latching position within an interval of about seven seconds, which is entirely too short a time to permit the necessary setting up 5 of the normal combination. Stop pin 580 holds finger 58 from being carried out of its useful zone of action when winding the movement.

It is to be understood that the tumbler mechanism employed in the present lock may be of any 10 approved ordinary construction save that the boss or extrusion 53 is formed on the number one tumbler disk. In the form herein exemplified, the mechanism used is a key change combination 15 tumbler mechanism which has a key change bar 67 associated therewith adapted to be operated in known manner by a combination changing key insertable through the cover of the casing. The key change mechanism is of ordinary construction, and forms no part of the present invention 20 therefore a detailed description is omitted.

From the foregoing, it will be noted that the device of the invention is particularly compact, (being here shown in Fig. 1 in exaggerated thickness) and in practice is readily contained in a 25 casing not in excess of one inch in thickness. The device is thus admirably suited for use on many chests or the doors of small compartments to be protected as well as to the larger structures that are commonly protected by combination or 30 time delay locks. The range of utility of the lock of the present invention is very wide. The time movements employed are desirably selected from present day commercially available time movements such as are embodied in window 35 lighting controls and in utility timers. The entire assembly is materially compacted by the disposition of the timing movement and the tumbler mechanism in close side by side relation in the case and by the employment of the inexpensive 40 flat members, namely, floating member 19, bell crank lever 29 and secret lever 28, all in a common plane in the normally wasted space below bolt member 38.

The structure is comparatively simple and is 45 foolproof in operation. The lock is useful as an ordinary tumbler combination lock, if desired, and it is at all times adapted to use as an anti-bandit lock or time delay lock which is furthermore selectively conditionable for such use at 50 any time in advance of the operation of the lock as well as instantaneously at the moment of an emergency. The secret combination serves to prevent a lockout in the event of a possible failure of the time movement but the simple 55 mechanism thereof is so coordinated directly with the time wheel of the time movement as to prevent improper use of the secret combination if an attempt is made to circumvent the operation of the properly functioning time mechanism. 60

What is claimed is:

1. A delayed opening lock comprising a combination lock including tumbler mechanism, a bolt and a bolt operating gate, a normally wound clockwork, means controlled by the initial direction of operation of the combination lock for selectively initiating running movement of the clockwork, gate baffling means controlled by the clockwork during running movement of the clockwork, and secret means operable by the tumbler mechanism for disabling the gate baffling means when the clockwork is arrested in partially wound condition. 65
2. A delayed opening lock comprising a combination lock including tumbler mechanism, a 70

2. A delayed opening lock comprising a combination lock including tumbler mechanism, a 75

- 1 bolt and a bolt operating gate, a normally wound 5
clockwork, means controlled by the initial direction of operation of the combination lock for selectively initiating running movement of the
clockwork, gate baffling means controlled by the clockwork during running movement of the clockwork, means operable by the tumbler mechanism for disabling the gate baffling means when the clockwork is arrested in a partly wound condition and means effective while the clockwork is in operation for rendering the gate baffling means operative after being disabled by said second gate.
2 3. A delayed opening lock comprising a combination lock including a bolt operating gate, a normally wound clockwork, a timewheel having a peripheral notch assuming a predetermined position when the clockwork is fully wound or fully unwound, a gate baffle floatingly mounted and having an abutment end yieldably contacting the periphery of the timewheel whereby the bolt operating gate is normally rendered inoperative when the clockwork is in partially wound condition, and lock operated means comprising a secret lever to disable the baffle when the clockwork is in partially wound condition.
3 4. A delayed opening lock comprising a combination lock including a bolt controlling gate, a normally wound clockwork, a floating gate baffle 15
beneath the lock and having an abutment finger adjacent the clockwork, a notched timewheel on the clockwork peripherally contacting the said abutment finger, whereby the baffle is rendered operative when the clockwork is in partially wound condition, means effective upon secret setting of the lock for disabling said baffle while clockwork is in last named position and means on the timewheel for immediate restoration of the baffle upon continued operation of the clockwork.
4 5. A delayed opening lock comprising a combination lock including a bolt controlling gate, a floatingly mounted gate baffle, a normally

wound clockwork, a timewheel movable with the clockwork urging the baffle to operative position when the clockwork is partially wound, a secret lever, an auxiliary gate actuatable by the lock upon setting to a secret combination for moving the lever whereby the baffle is disabled while the clockwork is in partially wound condition and means on the time wheel and in constant contact with the baffle for restoring the baffle to operative condition forthwith upon continued movement of the clockwork. 10

5 6. In a device of the class described the combination of a floatingly mounted gate baffle, a clockwork, a timewheel on the clockwork urging the baffle to operative position when the clockwork is partially wound, a frictionally mounted finger on the timewheel in constant contact with the baffle, and secretly operable means to shift the baffle from operative position to an inoperative position against the frictional 20 resistance of said finger when the clockwork is in partially wound condition, said finger, under the influence of continued operation of the timewheel, serving to quickly restore the baffle to operative position. 25

7. In a non-lockout mechanism for a delayed opening combination lock the combination with a bolt operating gate structure, of a floatingly mounted gate baffle, means yieldably urging the baffle to inoperative position, a normally wound 30 clockwork including a timewheel having a peripheral notch wherein the baffle enters when the clockwork is at rest in fully wound or in fully unwound condition, the periphery of said timewheel at all other times holding the floating 35 baffle in operative position, means operable for shifting the baffle from said operative position to an abnormal inoperative position and means frictionally supported on the timewheel and engaging said baffle for shifting the baffle from 40 said abnormal inoperative position upon continued movement of the timewheel.

CHARLES M. HIRN.
